JAMES DEVER, OF SIOUX CITY, IOWA

CATTLE-KILLING MACHINE

Application filed April 6, 1929. Serial No. 353,065.

The invention primarily has for its object to provide a novel machine for facilitating the killing of cattle, and which not only assures the accomplishment of the killing in a more certain and humane manner than has heretofore been practiced, but also assures the obtaining of the maximum of the potential market value of the cattle.

In its more detailed nature the invention resides in the provision of a novel turntable structure having provision thereon for impounding a suitable number of cattle, and means to impart rapid rotation to the turntable such as will serve to render the cattle substantially unconscious and thereby easy and safe to handle.

Other objects will in part be obvious and in part be pointed out hereinafter.

To the attainment of the aforesaid objects and ends the invention further resides in the novel details of construction, combination and arrangement of parts, all of which will be first fully described in the following detailed description, then be particularly pointed out in the appended claims, reference being had to the accompanying drawings in which:—

Figure 1 is a plan view illustrating the invention.

Figure 2 is a vertical cross section taken on the line 2—2 on Figure 1.

Figure 3 is a detail side elevation illustrating the turntable brake.

Figure 4 is an enlarged detail section illustrating one of the turntable supporting rollers.

Figure 5 is a view similar to Figure 4 illustrating one of the turntable guide members.

Figure 6 is a cross section of the turntable and superstructure.

In the drawings in which like numerals of reference indicate like parts in all of the figures, 1 designates a well which may be formed in the slaughter house floor in any approved manner, preferably with reinforce walls indicated at 2.

Within the well a circular track 3, preferably formed of T rail, is supported upon a circular I-beam 4 suitably secured upon the floor of the well.

Within the well and preferably flush with

the floor surface 1 provide a rotatable turntable comprising a circular floor 5 constructed of any suitable material and mounted upon a circular frame 6 preferably formed of a peripheral eight inch I-beam braced intermediate by longitudinal and transverse straight six inch I-beams as indicated at 7.

At equi-distantly spaced intervals of about three feet each depending roller bearing castings 8 are secured as at 9 to depend from the frame beam 6 into the well for rotatably supporting the turntable on the track 3. The supporting rollers carried by the castings are indicated at 10.

At equi-distantly spaced intervals, intermediate of the spaced roller bearing castings, depending guide members 11 are secured as at 12 to the circular frame beams 6 and have their lower ends extended down inside and in close relation to the track rail 3 and 70 having their lower end portions bent outwardly as at 13 to extend under the overhanging edge formed by the inside of the T rail. The rollers 10 serve to support the turntable for free rotation on the track 3 and the guides 75 11 bear such relation to the track as to assure against any tendency of the turntable to jump the track or get out of associated relation with its driving connections.

A frame plate 14 is supported beneath the turntable proper on a depending frame 15 formed of channel beams and braces. A ring gear 16 is secured to the under face of the plate 14 in any approved manner and in order to impart rotation to the turntable a driver pinion 17 meshes with the ring gear so that when the said pinion is rotated its rotation will be imparted to the turntable.

The pinion 17 is secured upon a power shaft 18 mounted in suitable bearings 19 supported 90 in the well and one end of the said shaft may be extended beyond the confines of the turntable into a suitable chamber 20 where it is equipped with a pulley 21 to which power may be applied by a belt 22 from any suitable 95 source of power (not shown).

A brake drum 23 may also be secured upon the shaft 18 within the chamber 20 and a steel brake band 24, studded on its inside face with fibre blocks 25, encircles the drum and is se- 100

cured at one end to a rigid mounting 26 and has its free end attached to a cable 27 which passes under a sheave 28 and secured to a brake lever 29 suitably fulcrumed as at 30. 5 Thus when the power has been cut off and it is desired to bring the turntable to a standstill the brake may be utilized to quicken the accomplishment of this purpose. In view of the high speed at which the turntable is 10 rotated and the great weight thereof, this brake equipment will greatly facilitate the accomplishment of the purpose of the invention.

Four angle iron uprights 31 are suitably 15 secured to the turntable framing and project vertically above the turntable to form corner posts for a cattle enclosure. Each side of the enclosure defined at the corners by the four uprights is completed by a pair of doors, 20 one of which is hinged to each adjacent pair of uprights, and each pair of doors being disposed to meet at the medial line. The doors are hinged as at 33 to the uprights and swing outwardly, and to prevent opening of the doors while the wheel is in motion, due to 25 centrifugal force, each door is equipped with a cleat 34 adjacent its free edge, and a bar 35 may be fitted into the cleats when the doors are closed to lock the doors against outward 30 swinging.

Within the enclosure formed by the uprights and hinged doors I provide a plurality of separating partitions 36 which divide the enclosure into individual cattle compartments or stalls. These partitions may of course, be omitted if desired.

In the slaughtering of cattle it is the common practice to strike the cattle a blow between the eyes with a heavy hammer. It 40 frequently happens that the cattle move their heads and the hammer blow is untrue and instead of a clean killing such as is possible with a single blow under ideal conditions four or five blows may be necessary to kill 45 the animals with the result that a clean killing is impossible and the brains removed from the animals will be blood clotted and impaired for commercial use.

It is the purpose of my invention to impound a suitable number of cattle in the enclosure upon the turntable and to rotate the said turntable at a rapid rate of speed, thus rendering the cattle unconscious and easy to handle and kill.

If desired the corner uprights 31 may be 50 braced by turn-buckle equipped cross rods 37.

From the foregoing description, taken in connection with the accompanying drawings, it is thought that the novel details of construction, the manner of use and the advantages of the invention, will be readily apparent to those skilled in the art to which it relates.

What I claim is:

35 1. A machine of the character described

comprising a turntable, an animal enclosure on the turntable, and means to impart rapid rotation to the turntable for the purpose described.

2. A machine of the character described 70 comprising a turntable, an animal enclosure on the turntable, means to separate the enclosure to constitute individual stalls, and means to impart rapid rotation to the turntable. 75

3. A machine of the character described comprising a turntable, an animal enclosure on the turntable, means to impart rapid rotation to the turntable, said means including a ring gear depending from the turntable, 80 a power shaft, a driver pinion on the shaft and meshing with the ring gear, and means to impart rotation to the power shaft.

4. A machine of the character described comprising a turntable, an animal enclosure 85 on the turntable, means to impart rapid rotation to the turntable, said means including a ring gear depending from the turntable, a power shaft, a driver pinion on the shaft and meshing with the ring gear, means to impart rotation to the power shaft, said power shaft being extended at one end beyond the confines of the turntable, and a braking device to act on the power shaft for the purpose of bringing the turntable to rest. 95

5. A machine of the character described comprising a turntable, an animal enclosure on the turntable, and means to impart rapid rotation to the turntable, said enclosure comprising corner uprights secured to the turntable, a pair of doors hinged to each upright and cooperating to form a walled enclosure defined at the corners by the said uprights. 100

6. A machine of the character described comprising a turntable, an animal enclosure on the turntable, and means to impart rapid rotation to the turntable, said enclosure comprising corner uprights secured to the turntable, a pair of doors hinged to each upright and cooperating to form a walled enclosure 110 defined at the corners by the said uprights, each of the doors hinged to a given corner upright being adapted to cooperate with one of the doors hinged to an adjacent upright to constitute one enclosure wall, the doors forming each said wall meeting at a medial line, and removable means to lock the doors against being thrown open by centrifugal force. 115

7. A machine of the character described comprising a turntable, an animal enclosure on the turntable, means to impart rapid rotation to the turntable, a well to receive the turntable, a circular track supported in the well and having an overhanging ledge, and rollers depending from the turntable at spaced intervals and adapted to ride on the said track. 120

8. A machine of the character described comprising a turntable, an animal enclosure 125

on the turntable, means to impart rapid rotation to the turntable, a well to receive the turntable, a circular track supported in the well and having an overhanging ledge, rollers depending from the turntable at spaced intervals and adapted to ride on the said track, and guide members depending from the turntable at spaced intervals intermediate of the rollers and having portions thereof extending under the track ledge.

9. A machine of the character described comprising a turntable having a floor, a circular rim and a fabricated reinforce center, an animal enclosure on the turntable and spaced inwardly of the edges thereof, a well to receive the turntable, a framing depending from the turntable into the well and including a frame plate, a circular track supported in the well and having an overhanging ledge, roller bearing members depending from the circular rim at equi-distantly spaced intervals and riding on the said track, guide members depending from the circular rim in equi-distantly spaced intervals intermediate of the roller bearing members and having portions to hook under the track ledge from the inside, a ring gear depending from the frame plate, a power shaft having a driver gear thereon and meshing with the ring gear, and means to impart rotation to the power shaft to rapidly rotate the turntable and render unconscious animals in the turntable enclosure.
